11 Claims. (CL. 170—160.2)

1

This invention accomplishes continuous control of adjustable mechanism by equal applications of actuating forces alternately to opposite sides of a movable member during status maintenance, and unequal applications of actuating forces alternately to opposite sides of the movable member during status changes. Fluid under pressure motivates the movable member when applied by a double acting valve connecting fluid pressure to one side of a servo mechanism and drain to the other side. Opposed solenoids when alternately energized control movement of the valve, and a rotating drum or other device with interrupting contacts effects alternate energization of the solenoid at some predetermined frequency or periodicity. A pick-off contact whose shiftable position is related to the governed speed of rotation of the drum alternately connects the solenoids with a source of electric current for equal periods of time during status maintenance, and differentially varies the length of solenoid energization during status changes. The surface of the rotating drum provides two contacts each of which have tapering portions that extend between like portions of the other but insulated therefrom, so that sequential engagement with a movable contact arm occurs on rotation of the drum. The pick-off contact rubbing on the drum at the mid-point engages equal portions of the two contacts to effect equal energization of the solenoids, and when shifted to one side of the middle of the drum successively engage contacts for unequal periods of time. The dwell on one contact will be shortened as the dwell on the other is lengthened. The change in solenoid energization is therefore differential. Manual means for shifting the point of pick-off and governor operated means for restoring the status maintenance condition, should there occur disturbing forces tending to change a predetermined condition, make it possible to closely control the adjustable mechanism at all times.

During status maintenance condition the drum rotates to deliver substantially equal electrical pulses to the opposed solenoids, first one and then the other, resulting in a reciprocating movement of the double acting valve which alternately connects the fluid pressure source for equal periods of time with opposite sides of the servo-mechanism. The opposite sides of the servo-mechanism receiving equal force applications, there is no resultant movement of the adjustable mechanism, and thus, the status maintained condition. With a satisfactory fre-

quency or periodicity of valve reciprocation there will be no objectionable vibration of the adjustable mechanism. For the majority of applications of the system of control, reciprocation of the valve at about twenty cycles per second (C. P. S.), has been found to be satisfactory, but the rate may be altered to suit specific conditions. During status change conditions, that is, when the adjustable mechanism is being changed to a different status, the drum rotates to deliver unequal electrical pulses to the opposed solenoids, that is, a longer pulse to one and a shorter pulse to the other, resulting in a reciprocating movement of the double acting valve which alternately connects the fluid pressure source for unequal periods of time with opposite sides of the servo-mechanism. The opposite sides of the servo-mechanism receiving unequal force applications, there will be a resultant movement of the adjustable mechanism toward the new status condition or position, which when accomplished, effects such manipulation of the drum or pick-off that the new status condition or position becomes a status maintained condition or position.

The adjustable mechanism in question may be some bulky piece of apparatus or other load that is to be moved to and held at a specific position as the status maintained condition, and movable to a different position or at a specific rate of speed as the status change condition. On the other hand, and as generally disclosed herein, the adjustable mechanism may be a rotatable device whose selected speed of rotation is the status maintained condition, and whose modification to a different selected speed or condition is the status change condition.

Further objects and advantages of the present invention will be apparent from the following description, reference being had to the accompanying drawings wherein a preferred embodiment of the present invention is clearly shown.

In the drawings:

Fig. 1 is a schematic view illustrating means, mechanism and a method of control by the invention disclosed herein.

Fig. 2 is a longitudinal sectional view of a rotary device, such as a variable pitch propeller, embodying control means and mechanism according to the instant invention.

Referring first to Fig. 1, 10 indicates a servomotor comprising a cylinder 12 enclosing a double acting piston 14 that divides the cylinder into a pair of expansion chambers 16 and 18, a piston 14 being mounted on a rod 20 adapted to move

a load device or adjust some particular mechanism here shown as a propeller blade, 22 mounted on a hub socket 24 to be driven by a shaft 26 in the direction of arrow A by means of a prime mover such as an engine or turbine (not shown). The expansion chambers 16 and 18 are hydraulically connected by passages 28 and 30 respectively with control ports 32 and 34 respectively in a valve sleeve 36. A pressure supply port 38 opens by passage 40 from a fluid pressure pump 42 whose intake is at 44. It is designed that the pump 42 operate continuously so as to supply fluid under pressure thru the port 38 into the bore 46 of the sleeve 36, a relief valve 47 being provided for safety purposes.

Cooperable with the valve sleeve 36 is a plunger or rod 48 having lands 50 and 52 properly spaced to coincidentally cover the ports 32 and 34 when the valve rod 48 is in the mid-position, or the port closing position. At each end of the rod 48 there are armatures 54 and 56 immersed in the magnetic field of solenoid windings 58 and 60 respectively, each of which when energized is capable thru its action upon the associated armature in shifting the rod 48 axially of the sleeve 36 so as to open either of the ports 32 and 34 to pressure from the passage 40 and the other port to drain. Solenoid windings 58 and 60 are joined by a wire 62 and communicate by a common connection 63 with one pole of a current source, such as a battery indicated at 64. The opposite ends of the solenoid windings 58 and 60 are connected by leads 66 and 68 to brushes 70 and 72 adapted to bear upon a contact drum 74. The contact drum 74 provides two contact members each of which have a continuous ring portion 76 and 78 surrounding the drum and each having triangular portions 80 and 82 interleaved on the surface of the drum but electrically insulated by a non-conducting boundary of insulation 84. The surface of the drum is therefore covered by a succession of alternating contact portions 80 and 82 of such extent as to be arcuately equally dimensioned along the middle of the drum such as indicated by the dash line 86.

A constant speed source, such as a constant speed motor 88 energized by the source leads 90, and adjustable for speed by the control 92, drives the drum contact 74 thru a shaft 94 in the direction indicated by the arrow B. A manual control 96 pivoted at 98 engages a collar 100 and is capable upon oscillation over a scale 102, of moving the drum 74 axially upon the shaft 94 of the constant speed device 88 such that a movable contact 104 remaining in a selected position on a slide rod 106 will engage at a shifted position upon the surface of the drum 74. The movable contact 104 is electrically connected to the other pole of the battery 64 by means of a lead 108 such that upon closure of a control switch 109 circuits may be completed between the current source 64, one of the contacts 80-82 and one of the solenoid windings 58-60, and back to the current source 64.

The movable contact 104 is automatically shiftable on the guide rod 106, and hence along the length of the drum 74, since it is mounted upon a carriage 110 actuated by a link 112 from a lever 114 pivoted at 116 and engaging a collar 118 on a movable shaft element 120 of a speed responsive device 122 driven by a shaft 124 in the direction of arrow C by means of a pinion 126 that is actuated by a gear element 128 from the propeller shaft element 26. In consequence, the speed responsive device 122 is a function of the

speed of shaft 26 which in turn is a function of the engine-propeller combination as here illustrated.

If there is a change in speed of rotation of the propeller and hence the shaft 26, there will be a change in the speed of rotation of the shaft 124 and hence the speed responsive device 122 will either expand or contract, which oscillates the lever 114 and shifts the contact 104 along the guide 106. As an example, and assuming an increase of speed, the shaft 26 will rotate faster in the direction of arrow A, and the shaft 124 will rotate faster in the direction of arrow C, which will cause the speed responsive device 122 to expand and oscillate the lever 114 in a clockwise direction to shift the movable contact 104 toward the left in Fig. 1. Assuming that the movable contact 104 has heretofore been engaging the drum 74 at the midpoint along the line 86 at which the dwells upon the contacts 80-82 are substantially equal, the left hand movement of the movable contact 104 will then differentially alter the successive engagement upon the contacts 80, 82 in such direction as to lengthen the dwell upon contact 80 and to shorten the dwell upon contact 82. Since every instance of contact 104 wiping over the rotary contacts 80, 82 energizes the associated solenoids 58, 60 in proportion to the length of dwell on the contact elements, and since every engagement of contacts 80, 82 with 104 effects energization of one of the solenoids with a corresponding port opening, then the alternate port openings at 32, 34 will be in proportion to the length of time of the corresponding contact engagement. Thereby, a succession of fluid pressure pulses is delivered to opposite sides of the piston in the servo motor. In consequence of this, solenoid 58 will be energized for a longer period of time than is the solenoid 60 energized. When the solenoid 58 is energized the valve plunger 48 is moved to the right connecting pressure port 38 with control port 34, and opening control port 32 to drain. Fluid pressure will then be applied for a longer period of time in expansion chamber 16 than is applied to the expansion chamber 18, which gives rise to a resultant movement of the piston 14 toward the left which operates to rotate the blade 22 in such direction as to increase its pitch, and thereby thru its increase of load reduces the speed of the engine-propeller combination. Conversely the reduction of speed of the shaft 26 reflects thru the speed sensitive device 122 to shift the contact 104 in the opposite direction or toward the right until it again coincides with the line 86 of equal contact length, which prevents any further shift of the blade pitch.

The speed setting at which movable contact 104 will effect a 50:50 pulse ratio can be varied by movement of lever 96 about pivot 98. For example, to increase the speed setting, the lever 96 is moved counterclockwise about pivot 98, as viewed in Fig. 1, and by reason of its engagement with collar 100 of shaft 94, drum 74 will be moved to the left. Under these conditions in order for contact 104 to engage the medial portion of the drum 74 which represents an on-speed condition, carriage 110 must likewise move to the left along slide rod 106. Movement of carriage 110 to the left can only be effected by the speed responsive device 122 and its associated linkage 120, 118, 114 and 112 when the device 122 responds to an increase in the rotative speed of propeller shaft 26 as selected by the lever 96. Conversely, the speed setting can be decreased by

moving the lever 96 clockwise about pivot 98, as viewed in Fig. 1. Moreover, it is to be understood that when the valve plunger 48 oscillates or reciprocates, it moves equal distances on opposite sides of a neutral or closed port position. When the ports 32 or 34 are open, they are wide open. In other words, the entire port area is either connected to drain or to the pressure port 38 and this is true regardless of whether the pulse ratio be 50:50 or 1:99. In this manner with a constant area opening, the fluid pressure pulses are determined by the length of time the solenoids 58 or 60 are energized resulting in a plunger dwell at the port open positions thereof.

It is to be understood of course, that the drum 74 is rotating at constant speed, as determined by the speed control 92. If the speed of rotation of the drum 74 is at such a rate that contacts 80 and 82 are successively engaged at every fortieth of a second, then the cycling of the pulses of current delivered to the solenoids 58 and 60 will be in the order of 20 C. P. S. each cycle including one energization of each solenoid. That rate of rotation is mentioned as an example and it is obvious that the rate may be varied by increasing or decreasing as desired. Rotating under constant speed, the cycling of the solenoid energization is constant, and if the movable contact 104 engages the drum at the midpoint thereof the successive alternate pulses will be equal or in a 50:50 relation. Shift of the movable contact 104 lengthwise of the drum will differentially alter the length of the pulses in either direction thru say 60:40, 70:30, and so on, until the movable contact 104 rides continuously upon either ring portion 76 or 78 when the pulse ratio will be 0:100 or represents continuous flow. That is to say, if the movable contact 104 is moved to either extreme end of the drum pulsing will cease, and one or the other of solenoids 58 or 60 will be maintained energized which will act upon the respective armature to maintain the associated port 32 or 34 continuously open.

In some installations, it is inherent in the structure that there is a continual urge for movement in one direction, which necessitates a continued application of pressure in one expansion chamber or the other to maintain the adjustable device in the status maintained condition. Under such conditions a slight shift of the movable contact 104 is made to one side or the other of the medial line 86 in order to maintain the apparatus in equilibrium position. That would incorporate a very slight difference in pulse length as the drum contact 74 is rotated, which would be just enough to allow sufficiently longer opening at one of the ports 32, 34 to provide the necessary sustaining pressure in one of the expansion chambers 16 or 18 to hold the blade 22 in the status maintained condition. As a specific example, propellers manufactured by one company, as a resultant of inherent factors, normally tend to shift toward a low pitch condition while in operation, which gives rise to the continued application of a relatively small force to the piston 14 which tends to move the blade mechanism toward increase pitch. That force just balances the forces normally tending to shift the blade to low pitch. In the illustrated embodiment this would mean application of sufficient counteracting pressure in the expansion chamber 18. Therefore, the movable contact 104 in the equilibrium position, that is, in the status maintained position, would ride upon the drum 74 slightly to the left-hand side of the medial

line 86 such that there would be delivered a pulse of slightly greater length to solenoid 58 than to solenoid 60. That would effect a pulse ratio other than exactly 50:50 relation (perhaps something like 51 to 49 as an assumed example) the longer duration of opening being for the port 34.

One adaptation of the instant system of control as applied to rotating structures of the propeller type is schematically illustrated in Fig. 2 where an engine driven shaft 26 projects thru anti-friction bearings 130 supported by an aircraft structure 132, and which shaft drivingly engages the hub 24 which is provided with sockets 134 for support of the variable pitch blades 22.

In this instance the blades 22 are rotatable in stack bearings 136 thru the longitudinal movement of piston 14 within the cylinder 12 and about a fixed spindle 138 extending radially from the hub 24. The piston is helically splined to the cylinder 12 at 140 and to the spindle 138 at 142 such that pressure application in the chamber 16 or 18 effects radial movement of the piston 14 with respect to shaft 26, and effects rotary movement of the blade 22 that drives a blade gear 144 engaging a master or coordinating gear 146. Control passages 28 and 30 connect the expansion chambers 16 and 18 with the ports 32 and 34 of the valve sleeve 36.

In this embodiment the valve sleeve 36 with its plunger 48 and solenoids 58, 60 are enclosed within a hydraulic regulator 148 made up of an annular plate 150 and a cover assembly 152 surrounding the shaft 26 and rotatable with the hub 24. Branches 154 and 156 from the passages 28 and 30 connect with a decrease pitch port and an increase pitch port respectively of a stand-by governor 158, while a branch 160 joins the passage 40 extending from the supply port 38 of the valve sleeve 36 to the pressure relief valve 47 and the pump 42. In this embodiment the pressure relief valve 47 has a feed back line 162 connecting with the increase pitch passage 28 of all servomotors such that the pressure potential of the pressure source line 40 is always capable of operating any device that is switched into the circuit. An extension 164 from the pressure source line 40 leads to a feather control valve 166 and controls the charging of an accumulator 168 by means of a passage 170.

Extending from the support 132 so as to be non-rotatable with respect to the regulator 148 there is an adapter assembly comprising a sleeve 172 surrounding the shaft 26 and providing a ring gear 174 inside of the regulator that meshes with a pinion 176 for operating the pump 42 upon rotation of the propeller. Journalled in the ring gear 174 are a plurality of screw shafts 178 that threadedly engage a control ring 180 that is capable of movement longitudinally of the shaft 26. Riding in a groove of the control ring 180 there is a shoe 182 for control of the stand-by governor 158, as well as a shoe 184 adapted to trip the feather control valve 166 when it is desired to either feather or unfeather the propeller blades. The screw shafts 178 are driven by an oscillatable ring 186 thru its engagement with pinions 188 carried by the screw shafts, the ring 186 having an arm 190 linked by 192 to a manually operated control lever 194. Oscillation of the lever 194 about its pivot 198 oscillates the ring 186 and rotates the screw shafts 178 which in turn moves the control ring 180 along the shaft to shift the position of the shoes 182 and 184. The shoe 182 moves a carriage 196 that modifies in response

with the standby governor 158, and if the carriage 198 is moved to the extreme left the standby governor is set for feathering shift so that tripping of the feather control valve 166 will allow a certain portion of the pressure from the accumulator 168 to flow thru 170, thru the valve 166, branch 164 and pump supply passage 40, branches 160 and 156 of the standby governor to passage 39 and chambers 18 of the servomotor, for turning the blade in the feathered position. When the lever 194 is moved in the opposite direction such as to move the control ring 180 out of the extreme left hand position the feather control valve 166 will again be tripped and the standby governor 158 will be so modified as to allow a portion of the fluid pressure and the accumulator 168 to flow thru passages 170, 164 and 40, the branches 160 and 154 of the standby governor and control passage 28 and chamber 16 for moving the blades out of the feathered position.

Movement of the carriage 198 to the extreme right hand will so modify the action of the standby governor 158 that the fluid pressure from the pump will be applied to the decrease pitch side of the servomotor to effect negative pitch shift. An intermediate position of the control ring 180 so modified the action of the standby governor 158 that it will occupy the range of governed pitch relation, and may be used as a rough governor in such position if the solenoid actuating control valve is disconnected. There is such overlap of the valve lands and ports of the standby governor that there is a band of no response by the governor which is served by the solenoid valve.

Power is led to the solenoid actuated valve by means of brushes 200, 202 and 204 supported by a brush carriage 206 mounted on the regulator cover 152. Slip rings 208, 210 and 212 carried by a bracket 214 mounted on the support 132 are engaged by the brushes and conduct current from the contact drum 74 and the current source 64 by 66, 63 and 68 respectively as shown and described. The speed sensitive device 122 is here driven by a shaft 216 and pinion 218 engaging a gear 220 on the propeller shaft 26. The pilot's hand lever 194 has an arm 222 that is linked by 224 to the manual lever 96 for shifting the drum 74, whereby correlation is effected between the pulsing governor and the standby governor.

While the embodiment of the present invention as herein disclosed, constitutes a preferred form, it is to be understood that other forms might be adopted.

What is claimed is as follows:

1. In a fluid pressure system for varying the load of a prime mover for maintaining constant speed, the combination comprising, a servomotor reversibly operable by fluid pressure to vary said load, a reciprocable valve having a pair of control ports connected to opposite sides of said servomotor for directing the flow of fluid pressure to opposite sides of said servomotor, means operable to continuously reciprocate said valve so that a succession of fluid pressure pulses are produced and delivered alternately to each side of the servomotor, said control ports being fully opened during each reciprocable movement of said valve, means operable to substantially equalize the duration of the alternating pulses delivered to each side of the servomotor for maintaining the load against change, and means operable to differentially alter the duration of the alternating pulses delivered to each side of the servomotor for changing the load on the prime mover.

2. In a fluid pressure system for varying the

load of a prime mover for maintaining constant speed, the combination comprising, a servomotor reversibly operable by fluid pressure to vary said load, a reciprocable valve having a pair of control ports connected to opposite sides of said servomotor for directing the flow of fluid pressure to opposite sides of said servomotor, means operable to continuously reciprocate said valve so that a succession of fluid pressure pulses are produced and delivered alternately to each side of the servomotor, said control ports being fully opened during each reciprocable movement of said valve, means operable to substantially equalize the duration of the alternating pulses delivered to each side of the servomotor for maintaining the load against change, and means operable to differentially alter the duration of the alternating pulses delivered to each side of the servomotor for changing the load on the prime mover and feed back mechanism operatively interconnecting the servomotor and said second and third recited means and operated in response to changing load for restoring the substantially equalized pulse duration when the changing load effects return to constant speed.

3. In a fluid pressure system, a fluid pressure operated motor, a control valve operatively connected with said motor for controlling the application of fluid pressure thereto, electromagnetic means operatively associated with said control valve for recurrently moving said control valve in opposite directions from a neutral closed position to alternately open said valve to apply fluid pressure impulses successively to one side of said motor and then to the other side, said electromagnetic means fully opening said valve during each recurrent movement thereof, and means operatively connected with said electromagnetic means to control the ratio of pulse duration that is applied to either side of the motor.

4. In a fluid pressure system, a servomotor, a reversing valve operatively connected to said motor for controlling the application of fluid pressure thereto, said valve having a pair of opposed armatures thereon and a pair of springs engaging said valve to normally maintain the said valve in its neutral closed position, electromagnets operatively associated with said armatures for attracting the same to open said valve in opposite directions, and means including a brush and alternately engaged commutating contacts connected each with the electromagnets for delivering a pulsating current to both of said electromagnets, alternately and equally to one and then to the other thereby to maintain rapid reciprocation of the control valve for equal and opposed pulse application to said motor with substantially no resultant motor movement, and means including a control member operatively connected with said commutating contacts for producing relative movement between said brush and the said commutating contacts to maintain rapid reciprocation of the control valve for unequal and opposed pulse application to said motor with a resultant motor movement in a direction to equalize the unequal pulse application.

5. In a fluid pressure system, a reversible servomotor, a control valve operatively connected to said motor having coacting valve members for controlling the application of fluid pressure to the said motor, resilient centering means operatively associated with the valve members to hold them in their neutral closed position, means operable to impart to one of the coacting valve members a series of rapidly repeated impulses

in opposite directions from said neutral position tending alternately to open said valve to one side of said reversible motor and then to open said valve to the other side of said reversible motor, said one of the coating valve members fully opening said valve during each of said impulses from the neutral position, and means operable to vary the ratio of the alternating impulses from an equal and opposite relation at which there is no resultant movement of the servomotor, to a relation of no impulses in one direction from the neutral position and continuous impulse in the opposite direction from said neutral position at which there is a resultant maximum movement of the servomotor.

6. In a fluid pressure system for varying the pitch of a blade in an engine-propeller combination, the combination comprising, a reversible servomotor operatively connected to said blade for adjusting the pitch of the blade in either increase or decrease pitch relation, a reversible slide valve operable to control the operation of the servomotor by applying fluid pressure to either side thereof, electromagnetic means operable to move the slide valve equal distances on either side of a neutral closed position to port open positions to direct fluid pressure to either side of the reversible servomotor, rotary contact means operable to energize the electromagnetic means, means for driving the contact means at constant speed, means including said rotary contact means for delivering a pulsating current to the electromagnetic means to effect alternate energization of said electromagnetic means for intervals of equal time duration while the blades are maintained against pitch change, means operable to effect alternate energization of said electromagnetic means for intervals of unequal time duration to effect a change in blade pitch, and means including mechanism operatively connected to said engine propeller combination and responsive to speed of rotation thereof automatically operable upon speed change of operation of the engine propeller combination for restoring the equal alternate energization of said electromagnetic means for establishing a non-changing operation of the engine-propeller combination.

7. In a fluid pressure system for varying the pitch of a blade in an engine-propeller combination, the combination comprising, a reversible servomotor operatively connected to said blade for adjusting the pitch of the blade in either increase or decrease pitch relation, a reversible slide valve operable to control the operation of the servomotor by applying fluid pressure to either side thereof, electromagnetic means operable to move the slide valve equal distances on either side of a neutral closed position to port open positions to direct fluid pressure to either side of the reversible servomotor, rotary contact means operatively connected to said electromagnetic means and driven at constant speed for delivering a pulsating current to the electromagnetic means to alternately energize the electromagnetic means to effect fluid pressure pulse applications alternately to the opposite sides of the servomotor, and means including a manually operable member and a mechanism operatively connected with said engine propeller combination for shifting the rotary contact means from a position effecting equal alternate pulse duration to a position for effecting unequal alternate pulse duration.

8. In a fluid pressure system for varying the

pitch of a propeller blade to effect substantially constant speed operation of an engine propeller combination, and in which a double acting servomotor responding to pressure differentials shifts the blade in pitch angle, the combination comprising, a solenoid actuated reversely operable valve connected in the fluid pressure system for directing fluid pressure to either side of the servomotor, means supporting the solenoid actuated valve within a regulator rotatable with the propeller, means including brushes and slip rings fixedly supported outside the regulator for transmitting electric current to the solenoid actuated valve, commutating means operatively connected with said engine propeller combination and responding to propeller rotation for reversely pulsing the solenoid actuated valve to rapidly and alternately deliver fluid pressure pulses to opposite sides of the servomotor piston, said commutating means including a member operable thereon for rendering the alternating pulses equal during on-speed operation of the engine propeller combination, and means including said member for rendering the alternating pulses differentially long and short for effecting corrective control.

9. In a fluid pressure system for varying the pitch of a propeller blade to effect substantially constant speed operation of an engine propeller combination, and in which a double acting servomotor responding to pressure differentials shifts the blade in pitch angle, the combination comprising, a hydraulic regulator rotatable with the propeller and supplying a pressure source for the fluid pressure system, a solenoid actuated reversely operable control valve connected in the system for directing source pressure to each side of the servomotor, means operable to reversely energize the solenoid actuated valve to apply pulses of fluid pressure alternately to each side of the servomotor, means including a brush and a commutating drum operatively connected to said actuating means for equalizing the duration of solenoid energization and hence the alternately delivered pulses so that the servomotor is held against resultant movement, and means operatively connected with the engine propeller combination and responding to off-speed of the engine propeller combination for shifting the brush relative to the commutating drum to vary the energization of said solenoid actuated valve so that differential pulses are alternately applied to the opposite sides of the servomotor whereby the resultant movement of the servomotor overcomes the error in off-speed of the engine propeller combination.

10. In a fluid pressure system for varying the pitch of a propeller blade to effect substantially constant speed operation of an engine propeller combination, and in which a double acting servomotor responding to pressure differentials shifts the blade in pitch angle, the combination comprising, a hydraulic regulator rotatable with the propeller enclosing the fluid pressure system and providing a source of fluid under pressure in said system, a reciprocating valve operatively connected to the source to the servomotor for applying pulses of fluid pressure alternately to one side and then the other side of the servomotor while the engine propeller combination is in operation, a pair of solenoids each operable to shift said reciprocating valve in an opposite direction, means operatively connected with said solenoids for alternately energizing the solenoids from a point outside of the regulator, means

11

operatively connected with the engine propeller combination and responsive to the speed of engine-propeller operation for proportioning the energization of said solenoids, whereby said solenoids receive substantially equal alternating pulses while the engine propeller combination is operating at on-speed and receive differentially unequal alternating pulses while the engine propeller combination is operating at an off-speed, and manual means operatively associated with said last recited means for selecting a speed setting for said engine propeller combination.

11. In a fluid pressure system for varying the pitch of a blade in an engine-propeller combination having a fluid pressure source and a reversible servomotor operatively connected to the blade for adjusting the pitch position thereof, the combination of control means for exactly positioning said blade including an oscillatable valve open to said source and having a pair of control ports connected each with one side of said servomotor, electromagnetic means continuously oscillating the valve equal distances to either side of a neutral closed position for alternately opening each port to source pressure during operation of the engine propeller combination, a reference speed device, contact means operatively connected with the reference speed device and said engine propeller combination and operable thereby, including a brush and a commutating drum operatively connected to said

5
